UNITED STATES PATENT OFFICE.

LOUIS BLOOM, OF VICKSBURG, MISSISSIPPI.

HANDLE FOR BOXES.

SPECIFICATION forming part of Letters Patent No. 236,296, dated January 4, 1881.

Application filed December 10, 1880. (No model.)

To all whom it may concern:

Be it known that I, LOUIS BLOOM, of Vicksburg, in the county of Warren and State of Mississippi, have invented an Improved Handle for Boxes, Drawers, &c., of which the following is a specification; and I do hereby declare that in the same is contained a full, clear, and exact description of my said invention, reference being had to the accompanying drawings, and to the letters of reference marked thereon.

The object of this invention is the construction of a handle which may be firmly attached to boxes, drawers, &c., the material of which is too thin to admit of the usual screw-fastening.

In the further description of my said invention which follows, reference is made to the accompanying drawings, forming part hereof, and in which—

20 Figure I is a vertical section of the device and a board which may represent a portion of a drawer or box to which the device is fastened. Fig. II is a front view of the invention and the board. Fig. III is a reverse view of Fig. II.

25 Similar letters of reference indicate similar parts in all the views.

A is a plate, having the perforated side extensions, *a a*, which, when bent at a right angle with the face of the plate, serve as lugs, 30 to which the handle B is secured. The plate A is also provided with a strip, *b*, extending from its upper edge, which, in connection with the plate A, is used to secure the device to the board C. The plate A is slotted near to its

lower edge, the said slot, which is represented by *c*, being of such size as to allow the insertion therein of the strip aforesaid.

To prepare the board to receive the device it is slotted at four points, as shown in the drawings. The plate A is then placed against the back of the board, the extensions *a* passing through the side slots, and the strips *b* through the upper one. The strip *b* is then bent down and its end passed through the lower slot in the board and through the slot *c* in the plate, after which it is drawn tightly and its end secured, by a screw or small nail, to the board.

In cases where the handle is not liable to be subjected to great strain, and the material to which it is fastened consists of pasteboard or very thin wood board, the screw may be omitted.

The handle is connected to the lugs by merely springing the lugs sufficiently apart to admit of the entrance of the pins *d* of the handle to the perforations *e* in the lugs.

I claim as my invention—

The plate A, having the perforated side extensions, *a*, strip *b*, and slot *c*, combined with the handle B, the said handle having pins *d*, adapted to enter the perforations *e* in the said extension, substantially as herein specified.

LOUIS BLOOM.
